UNITED STATES PATENT OFFICE

WILLIAM F. HELMOND, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed November 28, 1927. Serial No. 236,124.

This invention relates to carbon-holding devices for typewriting machines of the kind or type for writing upon a continuous web comprising a plurality of plies which may be 5 in the form of fan-folds, such, for example, as the typewriting machine forming the subject of the patent to Wernery & Smith, No. 1,132,055, of March 16, 1915, and more particularly the present invention is an improvement upon the carbon-holding device disclosed in the patent to Jesse A. B. Smith, No. 1,177,546, of March 28, 1916, for typewriting machines.

The machine disclosed in the Smith patent includes a carbon-carrying blade which is provided with two dowel-pins which fit in holes in the blade-bracket and a separately-mounted blade-manipulating finger-piece. In practice, these pins are mounted close together, being spaced about $\frac{7}{16}$ of an inch apart, and it is necessary that they be very accurately positioned; the pins are so close together that it is extremely difficult to prevent side play in the blade which must be held stationary and in parallel relation with respect to the platen to insure the correct positioning of the carbon-paper. It will also be noted that variations in spacing between the blade-pins and holes in the blade-brackets require enlargement of the holes or reduction of the pin-diameter, thus making it difficult to provide interchangeable blades, due to increasing the play in the mounting of the blade; because of the extreme accuracy in spacing required between the blade-pins and corresponding bracket-holes, interchangeability is impossible except at a great cost of production.

The primary object of the present invention is to improve and simplify the construction and mounting of the carbon-carrying blade on the supporting bracket, to facilitate the positioning and securing of the blade against play, and in parallelism with respect to the platen of the typewriter and so that the blades may be interchangeably positioned on the bracket. The construction includes a wider bracket, providing for a greater spread between the blade-pins and bracket-holes; the space between the pins and holes

is increased to an inch instead of $\frac{7}{16}$ of an inch. The blade is provided with a single downwardly-extending pin which can be fitted with just enough clearance to enter a hole in the bracket, which prevents sagging 55 of the blade. Upon an upper extension of this pin, a blade-manipulating finger-piece is secured, and, between the blade and this finger-piece, a carbon-sheet-clamping member is pivotally mounted. The bracket is 60 provided with an upstanding pin in spaced relation to the hole therein, and is engaged by the sides of a bifurcated end of the blade-member formed by an inwardly-extending slot, so that the sides thereof closely engage 65 the pin, the slot extending sufficiently to take care of any variation in the distances between the pins and holes of different brackets. This arrangement avoids the necessity for the extreme accuracy in interchangeably spacing the two pins and the two holes.

An advantage of the construction is the ready interchangeability of blades, since it is an easy matter to make the single pin and 75 slot of the blades interchangeable with the bracket-hole and locating pin. A further advantage of the construction resides in the reduction of the number of parts on the blade by utilizing a single blade-mounting pin, 80 upon an upward extension of which the carbon-sheet-clamping member is mounted, and the blade-manipulating finger-piece thereon holds the parts as stock-assembled units.

Another feature of the invention consists 85 in the provision of spaced clamping means along the carbon-carrying blade with the object of more securely holding a carbon-sheet against shifting or twisting with respect to the blade.

Other features and advantages will hereinafter appear.

In the accompanying drawings,

Figure 1 is a plan view of parts of a fan-fold typewriting machine having the present 95 improvements applied thereto.

Figure 2 is an elevation of a portion thereof, partly in vertical section.

Figure 3 is a perspective view of the improvements.

Referring to the accompanying drawings, the rearward extension 11 of an Underwood fan-fold typewriting machine is provided with rails 12 upon which a reciprocating carbon-carriage 13 travels in the usual manner and is provided with an operating handle 13^a, as disclosed in the Wernery & Smith patent hereinbefore referred to. The typewriter-platen is generally indicated by the reference letter P, and the fan-fold web and interleaving carbon-sheets by the letters W and C respectively.

On the ends of the reciprocating carbon-carriage are stepped brackets 14 and 15, upon which carbon-carrying blades 16 and 17 are mounted; the blades 16 being mounted on the left-hand bracket 14 and the blades 17 on the right-hand bracket 15 at the right-hand end of the carriage. The blades 16 and 17 are arranged to extend towards each other and overlap in the usual manner, and, preferably in practice, blades 16 are positioned above blades 17, the levels of the steps on brackets 15 not being quite as high as those of brackets 14 for that purpose.

As best shown in Figure 3, the left-hand bracket 14 is provided with a portion 18 extending to the left thereof, so as to materially increase the transverse dimension of each step 19, which step is provided with a hole 20 adjacent to its inner or right-hand end, and a pin 21 on the extending left-hand portion thereof. The bracket 15 is similarly constructed, but the extending portion is to the right side instead of to the left side, as will be readily understood. The drilling of the holes 20 and the drilling of the holes for the driven-in pins 21 in each bracket 14 and 15 may be done in the usual manner at one operation with a gig for hole-spacings of approximate accuracy without recourse to fine gaging operations with their associated limits for tolerance.

Each carbon-blade 16 comprises a longitudinal member having a downwardly-extending pin 22 adjacent to its left-hand end, which is fitted for a running-fit to enter one of the holes 20 in the bracket 14, and the extreme end of the blade-member is provided with a bifurcating slot 23, which closely engages the sides of a corresponding pin 21 on the extending portion of the bracket, the slot 23 being cut deep enough to provide a slight end clearance space 24 to the right of the pin 21, as indicated in Figure 1, so that the blade may be readily and interchangeably positioned on any of the steps 19 of different brackets without requiring extreme accuracy in the positioning of the pins 21 with respect to the holes 20 of these brackets. Blades 17 are correspondingly constructed to be mounted on the right-hand brackets 15.

The pin 22 is provided with a tang 22^a which, passed through a hole in the blade 16 and through a hole of corresponding diameter

in the finger-piece 26, is terminally riveted in said finger-piece where a hole 26^a of larger diameter is provided. An integral collar 26^b on the finger-piece forms a pivot on which the clip 25 is swingable for clamping a carbon C on said blade, while the finger-piece facilitates manipulation of the blade when mounting the latter on the bracket-member. The pin 22 provides a mounting member for the blade and the blade, with the assembled finger-piece and clip-member, becomes a stock-unit, thereby materially reducing the number of loose parts for the final assembly-operations.

The clip 25 is capable of swinging rearwardly away from the blade-member to permit a carbon-sheet C to be placed thereon with the end of the sheet doubled so as to extend on both sides of the blade-member. The blade-member is preferably provided with two or more spaced slots 27, and the clip with correspondingly-spaced detents or tongues 28 for engaging in said slots when the clip is in sheet-holding position, whereby both the clip and carbon-sheet are securely held. The spacing of the clamping members formed by the slots and detents provides a plurality of holding means along one end of the carbon-sheet, which positively insures the holding thereof in a manner so that the carbon will not be twisted sidewise with respect to the blade during the manipulation of the fan-fold web W and the carbon-stripping operations.

The free ends of the carbon-blades may be provided with usual web-slitters 29 when desired, and the slitters of the right-hand blade 17 may extend into clearance slots or notches 30 formed in the bracket 14. The slitters on blades 16 extend over the underlying right-hand blades 17 mounted on the bracket 15 and are supported by the latter blades.

Variations may be resorted to within the scope of the invention, and portions of the improvements may be used without others.

Having thus described my invention, I claim:

1. In a carbon-sheet-holding device for a fan-fold typewriting machine, the combination of a carbon-carrier having a supporting bracket and a series of sheet-holding blades removably attached thereto, said bracket and blades each provided with holding pins and each having openings for receiving corresponding pins of the opposite member, said pins and openings relatively arranged to permit the blades to be readily positioned on and removed from the bracket and to hold the blades parallel when in position on the bracket, and self-adapting means whereby variations in the distance between the pins and openings in the bracket may be compensated for by the pin and opening in the blade, thereby affording interchangeability

of blades with respect to the bracket without having to fit them.

2. In a carbon-sheet-holding device for a fan-fold typewriting machine, the combination of a carbon-carrier having a supporting bracket and a series of sheet-holding blades removably attached thereto, said bracket and blades each provided with holding pins and each having openings for receiving corresponding pins of the opposite member, said pins and openings relatively arranged to permit the blades to be readily positioned on and removed from the bracket and to hold the blades parallel when in position on the bracket, self-adapting means whereby variations in the distance between the pins and openings in the bracket may be compensated for by the pin and opening in the blade, thereby affording interchangeability of blades with respect to the bracket without having to fit them, and holding clips pivotally mounted on the pins on the blades for clamping the carbon-sheets to the blades.

3. In a carbon-sheet-holding device for a fan-fold typewriting machine, the combination of a bracket having an upwardly-extending pin at one side and a hole at its other side and a carbon-carrying blade having a pin adjacent to one end for engaging said hole in the bracket, and a bifurcating slot extending inwardly from its end which closely engages the sides of the upwardly-extending pin on the bracket for holding the blade in position thereon.

4. In a carbon-sheet-holding device for a fan-fold typewriting machine, the combination of a bracket having an upwardly-extending pin at one side and a hole at its other side, a carbon-carrying blade having a pin adjacent to one end for engaging said hole in the bracket, and a bifurcating slot extending inwardly from its end, which closely engages the sides of the upwardly-extending pin on the bracket for holding the blade in position thereon, and a holding clip pivotally mounted on the pin of the blade for clamping the carbon-sheet to the blade.

5. In a carbon-sheet-holding device for a fan-fold typewriting machine, the combination of a bracket having a hole adjacent one side thereof and an extending side member on the opposite side provided with an upwardly-extending pin adjacent its outer side edge whereby said pin is spaced at a distance from said hole, and a carbon-carrying blade having a pin adjacent to one end thereof for engaging said hole in the bracket and having a bifurcating slot extending inwardly from its end at a distance from said pin corresponding with the distance between the pin and the hole of the bracket, which slot closely engages the sides of the upwardly-extending pin on the bracket for holding the blade in position thereon.

6. In a carbon-sheet-holding device for a

fan-fold typewriting machine, the combination of a stepped bracket, each step having an upwardly-extending pin at one side and a hole at its other side, and a set of carbon-carrying blades, each having a pin for engaging a hole in the bracket and a bifurcating slot extending inwardly from its end for closely engaging the sides of the corresponding upwardly-extending pin on the bracket for holding the blade in position thereon.

7. The combination of a sheet-holding blade formed with a plurality of spaced slots or notches and a downwardly-projecting mounting pin adjacent one end thereof having an extension on the upper side of the blade, a finger-piece secured on said upper extension of the pin, and a holding clip pivotally mounted thereon between the blade and the finger-piece to permit said clip to swing into and out of position to clamp the sheet to the blade, said clip provided with a plurality of correspondingly spaced detents to enter said slots or notches to firmly clamp the sheet to the blade and prevent shifting or twisting of the sheet with respect thereto and also hold the clip in clamping position.

8. In a carbon-sheet holding device, the combination of a supporting bracket and a series of sheet-holding blades removably attached thereto, said bracket having a series of upstanding pins at its outer side and a corresponding series of holes along its inner side, said blades each formed with a plurality of slots or notches, a downwardly-projecting mounting pin adjacent one end of each blade for closely fitting into a hole in the bracket and each blade having a bifurcating slot extending inwardly from the end thereof, which closely engages the sides of one of the upwardly-extending pins on the bracket for holding the blades in position thereon, said pins having extensions on the upper sides of the blades, a finger-piece secured on said upper extension of each pin, and a holding clip pivotally mounted on each pin between the blade and the finger-piece to permit the clips to swing into and out of position to clamp the sheet to the blades, each of said clips provided with a plurality of correspondingly spaced detents to enter said slots or notches in the blades to firmly clamp the sheets to the blades and prevent shifting or twisting of the sheets with respect to the blades and also hold the clips in clamping position on the blades.

9. In a carbon-sheet-holding device for a fan-fold typewriting machine, the combination of a carbon-carrier having a pair of brackets, one bracket at each side of a fan-fold web to support a series of carbon-sheet-carrying blades between the plies of the webs, and means for detachably securing one end of each blade to a bracket for carbon-sheet renewal, said means including a locating pin and a locating hole on the bracket for each blade spaced apart with approximate accuracy, and

a pin and a slot in the anchoring end of each blade, said blade-pin entering a locating hole in the bracket for laterally supporting the blade, and said slot engaging the sides of the locating pin on the bracket for a close alignment of the blade, the slot in the blade justifying any variation in the spacing of the locating pin and the locating hole in the bracket.
